UNITED STATES PATENT OFFICE.

WILLIAM O. MYCUE, OF NIAGARA FALLS, NEW YORK.

CARBURETER.

1,109,356.

Specification of Letters Patent.

Patented Sept. 1, 1914.

Application filed October 19, 1911. Serial No. 655,610.

To all whom it may concern:

Be it known that I, WILLIAM O. MYCUE, a citizen of the United States, residing at Niagara Falls, in the county of Niagara and State of New York, have invented certain new and useful Improvements in Carbureters, of which the following is a specification.

My invention relates to carbureters and more particularly to that type used in connection with internal combustion engines.

The objects of my invention are, to provide simple and effective means whereby the proportion of air and gasoline or other volatile fluid, is maintained in proper proportion under all running conditions of the engine which it is to supply; and to provide means for retaining at all times a surplus quantity of gasoline or other volatile fluid in the carbureter and to so construct and arrange the parts that when starting the engine or running at low speed, all the air drawn through the carbureter will act directly upon the surplus gasoline or other fluid retained in or supplied to the carbureter, thus supplying a greater quantity to the engine under such conditions and obviating the necessity of "priming" the carbureter, particularly when starting the engine in cold weather.

Other objects are, to provide means for automatically governing the supply of gasoline and air, and regulating their proportioned quantities as required for the engine for most effective work under varying conditions; to provide a carbureter possessing the quality above mentioned which is simple of construction, durable, comparatively inexpensive of production, and economical in the use of gasoline or other volatile fluid; and to so construct the carbureter that it may be attached to the float-controlled feed-chamber in different relative positions.

With these objects in view the invention consists in certain features of construction and arrangement, and in the combination of parts to be hereinafter described and particularly pointed out in the subjoined claims.

In the drawings,—Figure 1 is a central vertical section of a carbureter constructed according to my invention, the same being attached to a float-controlled feed-chamber. Fig. 2 is a transverse section taken on line $x-x$, Fig. 1. Fig. 3 is a transverse section taken on line $y-y$, Fig. 1. Fig. 4 is a transverse section taken on line $z-z$, Fig. 1. Fig.

5 is a detached perspective view of the automatic governor valve.

Referring now to the drawings in detail, the reference numeral 6 designates the carbureter considered as a whole and 7 the float-controlled feed-chamber which may be of any common construction whereby the gasoline is maintained at a constant level in the carbureter.

60 The carbureter comprises a casing 8 which has two end cylindrical parts 9, 10 and an intermediate conical part 11 whose walls flare upwardly and provide a gradual upwardly-increasing mixing chamber 12 which 65 extends up into the upper cylindrical end 9 of the casing.

70 The lower cylindrical end part has inwardly-directed flanges 13, 14 at opposite ends in which are formed a series of openings 15, 16, respectively; the openings 16 in the lower flange 14 serving as air-inlets while the openings 15 in the upper flange admit both air and vaporized gasoline or 75 other volatile fluid to the mixing chamber.

80 Fitting into the flanges or connecting the same in a center tube 17 having its ends flush with the under side of the lower flange and the upper side of the upper flange, respectively, said tube serving to divide the 85 lower cylindrical portion of the casing into a circular central chamber 18 and an annular chamber 19 surrounding said central chamber. By preference, I secure an elbow or other air-inlet tube 20 to the lower end of 90 the casing. The circular central chamber 18 and the annular chamber 19 serve as a divided carbureting chamber, but it is to be understood that under certain conditions the annular chamber serves only as an air passage, as will presently appear.

95 The feed-chamber 7 has a feed-tube 21 extending laterally therefrom which is passed through the carbureting chamber, for 100 which purpose the casing has bosses 22 at diametrically opposite points provided with threaded bores opening into the annular chamber 19 and the tube 21 is externally threaded to permit of its being passed through said bores and through threaded 105 openings in the center tube 17 which are aligned with said bores. The tube 21 is shown integrally formed with the feed-chamber and has a comparatively large bore 23 extending from its outer end inward to a point 110 at least past the center of the carbureting chamber, and from said bore a small angular

passage 24 leads to the interior of the feed-chamber, part of said passage extending through the wall of said feed-chamber.

Entering the feed-tube 21 is a plug 25 which is preferably sweated into it and it has a threaded bore into which is threaded a needle-valve 26, the conical end of which is adapted to coöperate with the beveled outer end of the feed passage 24, as at 27. 10 The end of the plug is packed by means of packing material 28 packed around the needle-valve at the outer end of the plug by a gland 29 threaded onto the projecting end of said plug which is externally threaded at such point. The needle-valve has a knurled head 30 or other means for conveniently turning the same with a view of regulating the flow of gasoline to a well or surplus fluid chamber 31 which the inner portion of the bore 23 forms. 15 20

One or more apertures 32 are provided in the center tube 17 at a point above the gasoline feed tube 21 which connect the two portions of the carbureting-chamber, said 25 apertures serving at times as air-inlets for the center tube and at other times as mixture outlets for said tube.

The upper end of the casing 8 is closed with a removable lid or cover 33 fastened 30 in place in any approved manner; said lid or cover having a threaded central opening 34 into which is threaded a combined guide-rod and pressure regulator 35 having its lower portion reduced in diameter to form 35 a shoulder 37 and having said lower portion smooth to guide a governor-valve 38 which is seated against the upper flange or wall 13 which separates the annular portion of the carbureting-chamber from the mixing- 40 chamber. Said governor-valve comprises an inverted cup-like central portion 39 having preferably a central guide tube 40 extending downward from its upper end and an outstanding flange 41 at its lower end which 45 normally closes the openings 15 in the wall 13. The central cup-like portion of said valve has apertures 42 in its side and end walls for the admission of the vaporized gasoline and air to the mixing chamber.

50 Surrounding the guide-rod 35 is a coil spring 43 which exerts its pressure against said valve by reason of its lower end bearing thereagainst and the upper end against the shoulder on the guide-rod. The pressure of the spring against said valve is regulated by turning the guide-rod in the lid or cover 33, and for the purpose of retaining said guide-rod in any adjusted position, a jam-nut 44 is threaded thereon and impinges against said lid or cover. 55

The flange 41 of the governor-valve is somewhat smaller than the internal diameter of the casing 8 at this point so that a slight annular space separates the wall of 60 the mixing-chamber at its lower end from

the edge of said flange. Owing to the wall of the mixing-chamber flaring upwardly from its lower end the intervening space between the same and the edge of the governor-valve gradually increases in size as 70 the valve moves upward so that a greater quantity of gasoline and air may pass up into the mixing-chamber above said valve, this occurring when the engine increases its speed and the suction in the mixing-chamber 75 created thereby is sufficient to overcome the resistance of the spring 43, thus automatically admitting diluting air through the openings 15 and enlarging the passage for the escape of the carbureted air, thereby assuring a proper explosive mixture for the engine at all times. 80

The gasoline well or surplus fluid chamber 31 has an opening 45 through its wall so that air passing through the center tube, 85 has an aspirating effect on said well or chamber and draws out the gasoline therefrom, which is vaporized by the air currents and passes up into the mixing-chamber with the air through the openings 42 in the governor-valve. 90

The casing 8 has a mixture outlet-tube 46 which extends laterally from the cylindrical upper end thereof and has a throttle-valve 47 therein which is herein shown as a butterfly valve but may be any other construction serving the purpose. This outlet-tube is adapted for connection in any suitable manner with the ignition chamber or chambers of an engine. 100

In some types of automobiles certain explosive engines are used that will not allow sufficient room to arrange the carbureter as shown in Fig. 1 with respect to the float-controlled feed-chamber, or the space provided for the carbureter will not permit of connection with the engine when the mixture outlet-tube is extended in the direction shown in Fig. 1, and in such cases the carbureter casing may be given a quarter turn 105 to bring the air-tube and the mixture outlet-tube into a different position with respect to the feed-chamber. To permit of this the carbureter casing has a pair of diametrical bosses 48 arranged in a plane at right angles 110 to the bosses 22, said bosses 48 being internally threaded to permit the gasoline feed-tube 21 to be threaded therethrough. The casing has therefore two pairs of internally threaded bosses through either pair of 115 which the feed-tube 21 is passed and the bosses not in use for such purpose are closed with screw plugs 49. 120

The operation of the device is as follows: 125 When preparing to start the engine to which the carbureter is connected, it must be ascertained that the needle-valve 26 is in such relation to its valve-seat that gasoline can flow from the float-controlled feed-chamber 7 into the gasoline well 31 and when once 130

adjusted the further actuation of the needle valve is not necessary except for regulating the flow of gasoline to said gasoline well. The suction created by the engine causes air to be drawn into the carbureter, up through the center tube and also through the openings 16 in the bottom wall of the annular-chamber 19, thence through said chamber and through the apertures 32 in the center tube, the two currents of air commingling in the upper end of said center tube and acting upon the gasoline well to cause an aspirating effect upon the gasoline therein, which gasoline is drawn therefrom and passes with the air through the openings in the governor-valve, thence into the mixing chamber and from there into the engine through the mixture outlet-tube 46, the escape of the explosive-mixture thus created being regulated by the throttle-valve 47 within said outlet-tube. When starting the engine or when the engine is running at low speed the governor-valve remains seated against the wall dividing the mixing-chamber from the annular portion of the carbureting-chamber, thus compelling the gasoline and air to be drawn through the openings in the governor-valve; but when the engine increases its speed and the suction is thereby proportionately increased, it acts against the governor-valve and slightly raises the same against the resistance of the coil spring 43, thus admitting a greater amount of air into the mixing-chamber to correspond to the increased quantity of gasoline drawn from the gasoline well by reason of such increased suction.

When the engine is being started or running at low speed the apertures 32 in the center tube serve as air-inlets for said center tube, but as the suction increases, a portion of the air drawn up through said center tube escapes therefrom into the annular portion of the carbureting-chamber through said apertures, carrying with it a quantity of vaporized gasoline and as the mixture passing through said apertures enters the annular portion of the carbureting-chamber it commingles with the air passing through said annular portion, the whole passing out through the openings 15, around the edge of the flange of the governor-valve, and thence into the mixing-chamber. A portion of the air also travels directly through the center tube, carrying with it a portion of the gasoline drawn from the gasoline well, and passes underneath the flange of the governor-valve and around the edge thereof, and also through the openings in the cup-shaped portion of said valve, the two charges or portions being thoroughly commingled within the mixing-chamber and being drawn out through the outlet-tube. When the engine still further increases its speed the suction is increased proportion-

ately and draws the governor-valve up against the resistance of the spring 43 so as to further compress the latter and as the governor-valve gradually rises within the mixing-chamber the space between the edge of the flange of said valve and the wall of said mixing-chamber enlarges owing to the fact that the wall of said mixing-chamber is flared upwardly. This allows an increased quantity of gasoline and air to pass up into the mixing-chamber in proportion to the increasing demands of the engine due to its increasing speed, the valve rising in proportion to the increasing speed of the engine and enlarging the passage between the flange of the valve and the wall of the mixing-chamber, thus assuring at all times the proper proportion of air and gasoline as required by the engine for most effective work.

Having thus described my invention, what I claim is:

1. A carbureter comprising a casing having an intermediate upwardly-flaring portion serving as a mixing-chamber, a carbureting-chamber beneath said mixing-chamber having a center tube to provide a center-chamber and an annular-chamber between said tube and the wall of the casing, said annular-chamber having a perforated bottom wall and a perforated top wall and said center tube having an opening to connect said center-chamber with said annular-chamber, a gasoline feed-tube extending diametrically through said center and annular-chambers and having a gasoline well therein and a valve for regulating the flow of gasoline into said well, said gasoline well having an opening for the escape of gasoline therefrom, a governor-valve having a central cup portion provided with openings and an outstanding flange normally closing the perforations in the top wall of said annular-chamber, means for guiding said valve, a spring normally holding said valve in closed position, and means for regulating the tension of said spring.

2. A carbureter comprising a casing having an intermediate upwardly-flaring portion serving as a mixing chamber, a carbureting chamber beneath said mixing chamber having a center tube to provide a center chamber and an annular chamber between said tube and the wall of the casing, said annular chamber having a perforated bottom wall and a perforated top wall and said center tube having an opening to connect said center chamber with said annular chamber, means in said center chamber for causing air to be carbureted in passing therethrough, and a governor valve to control the mixture at the upper ends of said center and annular chambers.

3. A carbureter comprising a casing having an air inlet, a mixture outlet and a mix-

ing chamber having its wall flaring toward said mixture outlet, means for carbureting air passing through said casing, and a governor valve normally held at the small end of said mixing chamber and having a space between it and the flaring wall of said mixing chamber, said space gradually increasing in size as said valve is moved toward the larger end of said mixing chamber, said valve controlling the passage of carb-

reted air and diluting air into said mixing chamber.

In testimony whereof, I have affixed my signature in the presence of two subscribing witnesses.

WILLIAM O. MYCUE.
